UNITED STATES PATENT OFFICE.

HENRY WALDO ALSHOUSE, OF CUSTER, INDIANA.

GATE.

SPECIFICATION forming part of Letters Patent No. 380,306, dated April 3, 1888.

Application filed December 19, 1887. Serial No. 258,356. (No model.)

To all whom it may concern:

Be it known that I, HENRY WALDO ALSHOUSE, a citizen of the United States, residing at Custer, in the county of De Kalb and State 5 of Indiana, have invented a new and useful Improvement in Gates, of which the following is a specification.

The invention relates to improvements in gates; and it consists in the construction and 10 novel combination of parts hereinafter described, illustrated in the accompanying drawings, and pointed out in the appended claims.

In the drawings, Figure 1 represents a perspective view of a gate embodying my invention. Fig. 2 is a similar view showing the 15 gate raised.

Referring to the drawings by letter, A designates a gate, B being the hinge-post and C the latch-post thereof; and E are the rails of 20 the gate, the ends of which rails are respectively pivoted at the hinge end of the gate between the vertical bars F F and at the latch end of the gate between the similar bars, G G. f f are the hinges, and g is a latch of ordinary construction.

H is a rack-plate secured to the second rail of the gate, near the latch end thereof, and having the inclined rack-edge h on its upper edge. This rack-plate is formed from a single 30 piece of material having the vertical portions b c and the horizontal portion a, connecting the lower edge of the portion b and the upper edge of the portion c. The vertical portion c is secured to the side of the rail, the portion a rests on top of the rail, and the edge of the 35 vertical portion b is inclined upward from the latch end of the gate and provided with rack-teeth.

I is a pawl or detent pivoted at one end between the end bars, G, and having its other 40 end bifurcated, the arms of said bifurcation straddling the rack h, so that the teeth thereof engage in the notch i between the said arms. By means of said detent the front end of the 45 gate can be raised and held at any desired height, the end bars, F and G, always standing in vertical positions. To release the detent from the rack and permit the gate to descend, a cord, j, having one end attached to 50 said detent, is passed up over a loop or staple,

j', secured to the top rail of the gate, and a handle, J, is attached to the depending end of said cord.

K is a strong hinge composed of the thick plates k and k', the former of which is securely 55 bolted to the front edge of the gate, near the lower edge thereof, the latter being connected to its lower end by a suitable pintle. The joint is so constructed that the plate k' can turn no farther upward on the plate k than to 60 a position at right angles thereto.

L are a vertical series of mortises made in 65 the inner side of the latching-post C, each of which is adapted to receive the free end of the plate k' when the gate is raised to the corresponding position. By means of the said hinge and mortises the gate, when raised, is prevented from swinging laterally.

To release the plate k', the gate is raised sufficiently higher to withdraw the said plate 70 from the mortise. The plate will then fall against the edge of the gate and not interfere with the lowering thereof.

The gate by the described means can be raised or opened readily and quickly for the 75 passage of animals, and, being of very simple construction, cannot easily get out of repair.

By the detent and rack arrangement the height of the gate can be adjusted to allow the 80 passage of small animals only and bar the passage of larger animals, as may be desired.

In raising the gate one hand is placed thereon near the hinged end to prevent the hinges from disengaging, and the latch end of the gate is raised with the other hand.

Having described my invention, I claim—

1. The combination of the end bars and pivoted connecting-rails, the plate H, having the portion c secured to the side of one of the rails, the portion a on the top of the rail, and the portion b, extending upward therefrom having the inclined rack-edge h, stepped as shown, the detent pivoted at one end between the end bars and having its other end notched and engaging the rack h, the hook or eye j', 95 and the cord j, connected to the detent and passing through the said hook or eye, substantially as set forth.

2. The combination, with the hinge post B, the gate composed of the end bars, F G, and 100

rails E, pivoted at their respective ends to said bars, and the hinge K, composed of the plates k k', which hinge is secured to the bar G in such manner that the plate k' can turn upward no farther than to a position at right angles to the bar G, of the latching-post C, provided on its inner side with the vertical series of mortises L, adapted to receive the free end of the plate k' when the gate is raised to corresponding positions, as set forth.

In testimony that I claim the foregoing as my own I have hereto affixed my signature in presence of two witnesses.

HENRY WALDO ALSHOUSE.
